UNITED STATES PATENT OFFICE.

SIGNE BEATRICE SHAW, OF SEATTLE, WASHINGTON.

DESIGN FOR A DOLL.

Application filed December 29, 1923. Serial No. 8,191. Term of patent 7 years.

To all whom it may concern:

Be it known that I, SIGNE BEATRICE SHAW, a citizen of the United States, residing in the city of Seattle, in the county of King and State of Washington, have invented a new, original, and ornamental Design for a Doll, of which the following is a specification, reference being had to the accompanying drawings, forming a part hereto.

I claim:

The ornamental design for a doll, as shown.

SIGNE BEATRICE SHAW.
